UNITED STATES PATENT OFFICE.

CLAES WILLIAM BOMAN, OF BROOKLYN, NEW YORK, ASSIGNOR TO EAGLE PENCIL COMPANY, OF NEW YORK, N. Y.

DESIGN FOR A TIP FOR PENHOLDERS.

46,588.

Specification for Design.

Patented Oct. 27, 1914.

Application filed July 20, 1914. Serial No. 852,123. Term of patent 14 years.

To all whom it may concern:

Be it known that I, CLAES W. BOMAN, a citizen of the United States, residing at 1098 Greene avenue, Brooklyn, in the county of Kings and State of New York, have invented a new, original, an ornamental Design for Penholder-Tips, of which the following is a specification, reference being had to the accompanying drawings, forming part thereof.

The figure is a perspective view of a penholder showing my new design, the tip portion thereof in which my design is embodied being represented in full lines, while the handle portion thereof, which forms no part of the design, is represented in dotted lines.

I claim:

The ornamental design for a penholder tip, as shown and described.

CLAES WILLIAM BOMAN.
